ASH TRAY ASSEMBLY

William O. Collins, Falls Church, Va.
(6528 N. Kensington St., McLean, Va. 22101)
Filed Aug. 8, 1963, Ser. No. 300,746
1 Claim. (Cl. 131—241)

The present invention generally relates to a container assembly and more particularly to an ash tray capable of being orientated in stacked position.

An object of the present invention is to provide an ash tray assembly in which each ash tray is provided with a novel structure for supporting a cigarette by having a plurality of radial grooves in a ledge at the upper edge of the ash tray with the grooves being formed in down-turned corner edges thereof which project outwardly beyond the adjacent edges of the ash tray and which serve to terminate the groove surface inwardly of the corners of the ledge with the ledge also including a downwardly offset peripheral inner edge portion having radial grooves therein forming continuations in the corner grooves in the ledges.

A further object of the present invention is to provide an ash tray in accordance with the preceding object in which the downwardly offset portion of the ledge to the ash tray enables the base of an overlying ash tray in a stack of ash trays to be received and interengaged therewith for retaining the ash trays in stacked position with the ash trays also being capable of assembly with a base unit and cover unit to provide a decorative assembly as well as a utilitarian assembly.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a side elevational view of the ash tray assembly of the present invention;

FIGURE 2 is a vertical sectional view taken substantially upon a plane passing along section line 2—2 of FIGURE 1, on an enlarged scale;

FIGURE 3 is an exploded perspective view of the base unit and the first intermediate unit illustrating the relationship thereof;

FIGURE 4 is a perspective view of one of the intermediate units illustrating it in inverted position for use as an ash tray; and

FIGURE 5 is a side elevational view illustrating another type of assembly.

Referring now specifically to the drawings, the numeral 10 generally designates the container assembly of the present invention which includes a base unit generally designated by numeral 12, a plurality of intermediate units each generally being designated by numeral 14, and a cover or roof unit generally designated by the numeral 16.

As illustrated in FIGURE 2, the base unit 12 includes a bottom member 18 provided with a recess 20 in the bottom surface thereof together with a projecting flange 22 and also a second peripheral flange 24 extending beyond the projecting flange 22. The flange 24 is, in effect, an extension of the flange 22 but of less vertical height. Projecting upwardly from the bottom member 18 is a peripheral upstanding wall 26 which in the embodiment illustrated in FIGURES 1-4 is of square configuration. However, this shape may vary depending upon the type of assembly desired. For example, the peripheral wall 26 may be round as illustrated in FIGURE 5 and designated by numeral 26' or it may be octagonal, hexagonal, rectangular, frustoconical or any other suitable shape. Regardless of the

2

shape of the peripheral wall 26, there is provided a top edge 28 which is peripheral in nature and offset laterally outwardly of the wall 26 thus defining a radial offset transition portion 30 as clearly illustrated in FIGURE 2 and also in FIGURE 3. The base unit 12 is of unitary construction and is preferably constructed of ceramic material as is the entire assembly although other materials may be used if desired.

Each intermediate unit 14 includes a horizontally disposed plate 32 having a planar exposed surface 34. Projecting laterally from the surface of the plate 32 opposite from the planar surface 34 is a peripheral wall 36 which is spaced inwardly from the periphery of the plate 32. The peripheral wall 36 curves laterally outwardly as it extends away from the plate 32 and thus defines a rather concave external surface 38 and a convex internal surface 40. Thus, the outer end of the peripheral wall 36 defines a perimeter generally equal to or greater than the perimeter of the plate 32. A laterally extending ledge 42 merges with the outer edge of the peripheral wall 36 and extends outwardly in a generally horizontal manner and terminates in a curved peripheral lip 44 which curves back toward the plate 32. The corners of the ledge 42 are curved downwardly considerably more than the central portion and also having a greater radial extent than the central or intermediate portion and, in fact, the central portions may be considered substantially straight while the corner portions are curved the most as indicated by numeral 46 although the corner portions 46 merge into the central portion 44 as illustrated in FIGURES 3 and 4. The interior of the wall 36 is provided with an inwardly extending flange 48 spaced longitudinally in relation to the ledge 42 thus defining a peripheral recess 50 for telescopically receiving and engaging the peripheral wall portion 28 of the base unit 12 and in the case of an upper intermediate unit, the recess 50 telescopically receives and interlocking engages the periphery of the plate 32 with the planar surface 34 thereof engaging the surface of the flange 48.

When the intermediate units are employed in forming a pagoda, they are orientated in the manner illustrated in FIGURES 2 and 3 with the recess 50 facing downwardly for telescopic engagement and interlocking engagement with the peripheral wall portion 28 of the base unit 12 in the case of the lowermost intermediate unit 14. The uppermost intermediate unit telescopically engages with the plate 32 for interlocking the intermediate unit. The downwardly and outwardly curved peripheral walls 36 are then in a position to simulate a pagoda construction with the ledges 42 and corners 46 serving to further simulate actual pagoda construction and also, the bottom edge portion of the plates 32 are exposed below the ledges 42 to further provide a simulation of a pagoda construction.

The cover or roof assembly 16 includes a hollow roof or wall structure 52 of general pyramidal configuration and provided with an outwardly extending ledge 54 corresponding to the ledge 42 with the outer edge and outer end portion of the edge of the ledge 54 being slightly upwardly curved as at 56 similar to the structure of the edges 44 of the ledges 42. Also, the corners 58 are further curved upwardly as are the corners 46 on the ledges 42. At the apex of the peripheral wall structure 52, there is provided an upstanding tapered projection 60 having a lower spherical portion 62 and a ball-like oval-shaped member 64 at the upper end. This structure forms a handle for the roof or cover assembly 16 and also forms a spire for the roof of the pagoda when assembled. Also, an inwardly extending flange 66 is provided similar to the flange 48 and the flange 66 is spaced inwardly from the bottom of the ledge 54 thus forming

a recess 63 corresponding to the recess 50 for interlocking engagement with the plate 32 on the uppermost intermediate unit and also for telescopically and interlocking with the wall portion 28 of the base unit 12 when the cover or roof assembly 16 is employed with the base unit 12 to form a covered dish.

All of the units forming the pagoda will have the same wall configuration, for example, as illustrated in FIGURES 1-4, there are four walls generally defining a square pagoda. However, as illustrated in FIGURE 5, the pagoda units may be circular in configuration or may be octagonal, hexagonal or any other suitable shape. In each instance, each intermediate unit, which may vary in number, is of substantially identical construction and the cover unit 16' is usable either with the uppermost intermediate unit or with the base unit 12'. Also the particular projecting ledge and upwardly curved structural components incorporated into the ledge may vary as desired. For example, FIGURE 5 illustrates what may be considered a scalloped edge for the ledge with there being a plurality of upwardly curved points 70 for illustrating another type of pagoda and also, the roof and spire construction may be varied as desired for varying the handle structure for the cover or lid assembly and also for varying the appearance of the pagoda. The various components may be colored in a particular manner to provide for different appearance characteristics such as occur in various pagoda constructions.

Also, the corner of the bottom surface of the ledges is provided with radial grooves or recesses 72 which define cigarette holding areas when the intermediate units are inverted and used as a cigarette or ash tray. The grooves 72 are horizontal and terminate inwardly of the corners 46 and continue across the offset surface or recess 50 to the inner edge of the ledge. Moreover, the internal configuration of the peripheral wall structure may be varied to provide a smooth internal surface for ease of cleaning if desired or provide a particular configuration of internal surface for a particular use. The ledges 42 and their curved corners and curved edges 44 form a handle for enabling secure grasping of the intermediate units such as when using the device for various purposes and also, the plate 32 which becomes a base plate when the intermediate units are inverted as illustrated in FIGURE 4 for use as an ash tray stabilizes the structure to prevent it from tipping over. Also, the contour of the ledge may vary and may have an arcuate curvature throughout the surface area thereof if desired but in any event, the flange 48 will define a flat horizontal surface for engaging either the upper edge of the wall portion 28 or the planar surface 34 of the plate 32. In order to form the pagoda, the base unit is positioned initially and if the cover assembly 16 is employed thereon, it is removed and the intermediate units as illustrated in FIGURE 4 are taken one at a time and inverted to the position illustrated in FIGURE 3 and then brought into telescoping interlocking stacked relationship to the base unit and the underlying intermediate units as the case may be. The cover unit 16 is then placed on the uppermost intermediate unit thereby forming a simulated

pagoda as illustrated in FIGURES 1 and 2 and also in FIGURE 5.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

A cigarette ash tray comprising a plate-like base of polygonal configuration, an upstanding and outwardly flared wall member adjacent each side edge portion of said base, the wall members having vertical side edges which are joined to form corners defining a hollow interior receptacle portion for receiving cigarette ashes, a generally horizontally disposed ledge on the upper edge of each wall member, said ledges projecting outwardly beyond the wall members with the adjacent ends of the ledges being joined and forming ledge corners, said ledge corners curving downwardly and outwardly and having a radial extent which is greater than that of the intermediate portions of the ledges, the innermost portion of each ledge having a downwardly offset recess in the top surface thereof extending to the inner edge of the ledge defining a peripheral shoulder adapted to receive the base of an overlying ash tray when a plurality of ash trays are stacked for positioning and retaining the base of the overlying ash tray in aligned position thereon, each ledge corner having a radial groove formed therein with the surface of the groove being horizontal whereby the downward curvature of the ledge corner forms an outward taper in the groove with the outer edge of the groove terminating inwardly of the outer edge of the ledge corner whereby the outer end of a cigarette placed in the groove will be spaced from the ledge corner, portions of the downwardly offset recess in the inner periphery of the ledge having a groove therein forming a continuation of the cigarette groove in the ledge corner for receiving and positioning the inner end of a cigarette placed in the groove in the ledge corner.
